UNITED STATES PATENT OFFICE.

EDWIN F. WHITE, OF HOLLIDAYSBURG, PENNSYLVANIA, ASSIGNOR OF ONE-
THIRD TO EDWARD H. L. PAGE, OF HOLLIDAYSBURG, PENNSYLVANIA,
AND ONE-THIRD TO ROBERT LEE WALKER, OF DUNCANVILLE, PENN-
SYLVANIA.

HOT-WATER HEATER.

No. 846,370.

Specification of Letters Patent.

Patented March 5, 1907.

Application filed December 13, 1905. Serial No. 291,607.

To all whom it may concern:

Be it known that I, EDWIN F. WHITE, a resident of Hollidaysburg, in the county of Blair and State of Pennsylvania, have invented a new and useful Improvement in Hot-Water Heaters; and I do hereby declare the following to be a full, clear, and exact description thereof.

My invention relates to certain improvements in hot-water heaters, such as used for any regular hot-water heating system, its object being to provide heating-boiler adapted for rapid heating of the water, proper circulation of the same, to overcome the gathering of air in any portion of the boiler itself and the consequent knocking or noise arising from the same, and provide a sectional boiler which can be easily erected and can be used, if desired, without the necessity of inclosing in brickwork, while the body thereof can be insulated so as to prevent the radiation of heat.

To these ends my invention comprises, generally stated, a hot-water heater formed in hollow sections each provided with outer vertical legs extending up to a continuously upwardly curved cross portion or waist, a central vertical riser and two side risers extending up from the waist portion and connected to an upwardly-curved top portion, the side risers being set in from the vertical legs, and a fire-grate of the full width between said legs, as well as in other improvements to be hereinafter described.

To enable others skilled in the art to employ my invention, I will describe the same more fully, referring to the accompanying drawing, in which—

Figure 1 is a front view of a boiler embodying the invention. Fig. 2 is a side view of one of the sections set in place within the heater. Fig. 3 is a longitudinal section on the line 3 3, Fig. 2. Fig. 4 is a vertical cross-section on the line 4 4, Fig. 3, and Figs. 5 and 6 are detail views.

The boiler-sections forming the improved heater are made of separate castings adapted to be nested together and they may be inclosed in any suitable way. They are specially adapted, however, for being nested together in such way as to form a complete boiler without brick inclosure, the main portion of the boiler being covered with asbestos

or like filling cement, the boiler-sections providing means for supporting the same.

The boiler is formed of different sections 1, the sections being of the same shape and interchangeable, and, as shown, it has the base-castings 2, supporting these sections 1, and the front base-casting 3, provided with an ash-pit door 4. Above this front base-casting 3 is the cross-leg 5, hereinafter referred to, and supported thereon is the front box 6, containing the fire-door and forming the front of the heater. At the back of the furnace is the back box 7, which also will be hereinafter described. The hollow sections forming the heater proper are each provided with the outer vertical legs 8, which extend up practically to near the top of the fire-chamber, where they connect with the continuously upwardly curved waist portion 9, forming the roof of the fire-box, from which there are two side risers 10, extending up to the upwardly-curved top portion 11, there also being the central riser 12, connecting top of the waist portion 9 to the top portion 11. As illustrated in the drawings, the curved waist portion 9 starts below the side risers 10, and it is formed on a gradual upward curve or arch extending from the legs 8 to the central riser 12 and forming a continuous upward passage to that central riser. The vertical side risers 10 extend up from this waist portion 9 some distance in from its point of junction with the legs 8, the side risers being thus set in, forming the upper portion of the section narrower than the lower portion thereof, while making it possible that the connections between the legs 8 and the waist 9 shall be upon gradual upward curves which merge into the side risers 10 and continue beyond the same on an upward curve to the central riser 12. By this construction the central space 13 below the waist portion 9 forms the fire-chamber, while the spaces 15 between the central riser 12 and the side risers 10 form the return-flues to the smoke-outlet 16. The outer vertical legs thus form the walls of the hot-water heater and the walls of the fire-chamber 13, which extends for the full space between said outer vertical legs, the grate extending, as shown, for the full width of the fire-chamber, so that the portion of the heater where the greatest heat is absorbed is directly over the fire-chamber,

this including the waist portion 9 and the vertical risers therefrom inclosing the return-flues, the main body of the water to be heated being brought directly over the fire, which causes the very rapid absorption of the heat therefrom, while giving an extremely simple construction and one in which the water can always pass in upward course from the bases of the legs to the upper part of the heater 10 through the several sections thereof without possibility of it being pocketed or held in its course. As shown in the drawings, to inclose the spaces between the sections, which are spaced sufficiently apart to permit the 15 contact of the flame and heated gases with nearly the entire surface of each heater-section, continuous webs or flanges 17 are formed near the outer edges of the sections, running vertically along the leg portions, 20 then on an upward curve along the junction between the leg portions and waist portions of the side risers, and then around near the upper edge of the top portion 11. There is also a cross web or flange 18 extending across 25 from the flanges 17, near the top line of the waist portion 9 and connecting the two, so as to close communication between the fire-chamber 13 and the return-flues 15. These flanges are formed on each side of each section, 30 and the flanges of two sections contact with each other as the sections are built up, and so form the continuous water-heater. It will be noticed that the flanges 17 are set in slightly from the outer edge of the heater, 35 leaving the spaces 19 to be filled with asbestos or other cement 20; by which the sections are insulated.

To form a water connection at the base of the vertical legs 8 and between the legs of the 40 front section and so give circulation across the lower portion of the boiler, the cross-leg 5, above referred to, is employed, this being a hollow casting fitting up with the base of the legs and having suitable water connections therewith, so that circulation can be maintained from any suitable inlet-pipe, as the pipe 21.

The different sections are arranged to communicate with each other at the bases 50 of their vertical legs 8 and centrally of the top portion 11, suitable circulation-passages 22 23 being formed and these portions of the sections being fitted to each other by suitable rabbeted joints. The sections as thus constructed are held together by means of suitable bolts 24, extending through the passages 22 23 and bearing upon suitable caps 25, closing these passages in the end sections. The several sections composing the 60 water-heater are thus secured by three bolts, one at the base of each leg and one at the top of the boiler central thereof. It is found that in thus bolting together the several sections an easier connection between 65 them is obtained than where the bolting is

of rectangular form, overcoming defects in the casting, while the sections are less apt to be drawn apart by warping. The cross-leg 5 is bolted to and closes these passages at the bases of the legs of the front sections.

The front box 6, resting, as above stated, upon the cross-leg 5, can be secured in suitable way to the flange 17 of the front heater-section, such as by straps 26. It has the cross-web 27 uniting with the cross-flange 18 75 on the front section, so as to form a continuous return-flue over the fire-chamber. The smoke-passage 16 is formed at the upper end of this front box 6. The back wall 80 of the heater is shown as formed of the box 17, which has the side and top flanges 28, corresponding in position to the flanges 17, so as to close the rear portion of the boiler, and this back wall is secured to the boiler-sections by means of straps 29, connecting 85 the flanges 17 and 28.

To form the grate-bar supports, suitable lugs 30 are cast upon one of the front cross-castings and upon the back box 7, according to the desired height of the grate within the 90 fire-chamber. In Figs. 2 and 4 this grate is shown as placed below the vertical legs 8. In Fig. 3 it is shown as placed in line with the base portion of said legs.

To properly insulate the heater, the base-casting, such as the castings 2, may be formed recessed on their outer faces, such recessed portions being filled with brick, as shown at 31. The construction also provides a desirable means for insulating the 100 boiler-sections and yet permitting free circulation of heat practically around the entire hollow portions thereof exposed within the fire-chamber or return-flues. As above stated, the web-flanges 17 are set in only a 105 short distance from the outer edge of the sections. By this construction the recesses 19 are formed extending from the bases of the sections upwardly over the same, which form proper seats for holding the asbestos or like 110 insulating cement or filling, which can be simply filled within the same or extended over the whole heater-surface, being held to place by means of such recesses 19, which insure the proper support of the cement 115 filling.

In the use of the heater the fire generated in the fire-chamber 13 can circulate upwardly around the hollow sections, passing upwardly around the vertical leg portions 8 and being directed in upward course around the waist portions 9 and following in course back along the different sections to the throat portion 32, connecting the fire-chamber with the return-flues, and passing thence forward 120 around the upper portions of the hollow sections to the escape-flue 16. In thus circulating through the heater the flame and heated gases have opportunity to contact 125 with practically all of the outer walls of the 130

hollow sections and with all of the central risers 12 in each section, while the sections are spaced apart sufficiently to give free opportunity for such circulation and contact of the flame and heated gases with those walls. By means of the gradual upwardly-curved waist portion 9 the proper curvature in the upper portion of the fire-chamber to cause the flame and heated gases to travel along through the same to the throat 32 is provided, and at the same time the circulation of the water in each hollow section is made practically perfect. The main body of the water to be heated is brought directly over the fire, and a broad low fire-box can be employed in which the flame and heated products can contact with the greater portion of the walls of the different sections, so insuring the rapid absorption of the heat from the gases by the water and obtaining extremely high heating results. The heated water rises in its circulation within the vertical legs, and in its passage either upwardly in the waist portion or in the side and central risers 10 and 12 into the top portion 11 the water passes in either vertical or regular upward incline without encountering any abruptly-curved portion in which air might gather and lead to knocking or noise within the boiler, and a free and rapid circulation is induced through the provision of the upwardly-curved waist portion and the set-in side risers leading, as illustrated, into the curved top portion. At the same time proper cross circulation is obtained through the cross-leg 5, and the water may be drawn off for circulation through any suitable pipe, such as the pipe 34, and returned through the pipe 21 to any portion at the base of the boiler. In this construction the spaces between the different sections are enclosed by metal and those portions properly protected by the asbestos filling within the recesses 19 and liability of great radiation from the heater is overcome.

Practical use of the heater has proven it to give free circulation for the gases and rapid absorption of the heat by the water and economical heating. The size of the heater can of course be regulated by the number of sections employed.

What I claim is—

1. A hot-water heater formed of hollow sections provided with outer vertical legs extending up to a continuously upwardly curved cross portion or waist, a central vertical riser and two side risers extending up from the waist portion and connected by an upwardly-curved top portion, the side risers being set in from the vertical legs.

2. A hot-water heater formed of hollow sections provided with outer vertical legs extending up to a continuously upwardly curved cross portion or waist, a central vertical riser and two side risers extending up

from the waist portion and connected by an upwardly-curved top portion, the side risers being set in from the vertical legs, the vertical legs forming the outer walls of the fire-chamber, and a grate extending the full width between said legs. 70

3. A hot-water heater formed of hollow sections provided with outer vertical legs extending up to a continuously upwardly curved cross portion or waist, a central vertical riser and two side risers extending up from the waist portion and connected by an upwardly-curved top portion, the side risers being set in from the vertical legs, the connections between the legs and waist being on a gradual upward curve merging into the two side risers and central vertical riser. 75

4. A hot-water heater formed of hollow sections provided with outer vertical legs extending up to a continuously upwardly curved cross portion or waist, a central vertical riser and two side risers extending up from the waist portion and connected by an upwardly-curved top portion, the side risers being set in from the vertical legs, the connections between the vertical legs and risers extending up from the waist portion being formed on a gradual upward curve or arch. 80

5. A hot-water heater formed of hollow sections provided with outer vertical legs, a continuously upwardly curved cross portion or waist and risers above the same connected with an upwardly-curved top portion, each said section having on each side of it a web flanged near the outer edge thereof to form connection with the next section, said webs when united forming an outer insulating-recess. 90

6. A hot-water heater formed of hollow sections each provided with outer vertical legs extending up a continuously upwardly curved cross portion, a central riser and two vertical side risers extending up therefrom connected to an upwardly-curved top portion and having spaces for forming a fire-chamber and return-flues, said sections having on each side thereof near the outer edge flanges extending out to form the meeting edges of the sections and having a cross flange or web extending between said flanges 110 in the line of the waist portion of the section. 115

7. A hot-water heater formed of hollow sections provided with vertical legs extending up to a cross portion or waist, and having above the same a top portion, said sections having connecting-passages at the bases of the legs and at the center of the top portion, and connecting-bolts passing through said passages to secure the sections together. 120

8. A hot-water heater formed of hollow sections provided with vertical legs extending up to an upwardly-curved cross portion or waist, a central vertical riser and two side risers extending up from the waist portion and connected to an upwardly-curved top 125 130

portion, said sections having connecting-passages at the bases of the legs and at the central top portion and a separate hollow cross-leg adapted to extend across at the base of the leg portions, said cross-leg having formed with it a support for the grate-bars.

9. A hot-water heater formed of hollow sections provided with vertical legs extending up to an upwardly-curved cross portion or waist, a central vertical riser and two side risers extending up to an upwardly-curved top portion, a continuous flange extending

out from each side of each section near its outer edge for union with the other sections and a back plate or box having an inwardly-extending flange corresponding to such flanges and connected thereto by straps. 15

In testimony whereof I, the said EDWIN F. WHITE, have hereunto set my hand.

EDWIN F. WHITE.
